UNITED STATES PATENT OFFICE.

HERMAN G. S. DENKER, OF BALTIMORE, MARYLAND.

SHOE-TREE.

1,121,233.

Specification of Letters Patent. Patented Dec. 15, 1914.

Application filed March 28, 1913. Serial No. 757,296.

To all whom it may concern:

Be it known that I, HERMAN G. S. DENKER, a citizen of the United States, residing at Baltimore, in the State of Maryland, 5 have invented certain new and useful Improvements in Shoe-Trees, of which the following is a specification.

This invention relates to improvements in shoe trees.

10 The invention consists of the novel construction and arrangement of the parts and combination of parts hereinafter more fully set forth in the following specification and pointed out in detail in the appended claim.

15 In the accompanying drawings,—Figure 1 is a side elevation of my invention. Fig. 2 is a top plan view of the stationary foot piece. Fig. 3 is a bottom plan view of the pivoted toe piece. Fig. 4 is a detail view 20 of the threaded rod for raising and lowering the pivoted toe-piece. Fig. 5 is a detail plan view of the adjustable wedge. Fig. 6 is a side view of Fig. 5.

Referring to the accompanying drawings, 25 forming part of this specification, and in which like reference numerals designate like parts throughout the several views, 1 designates the foot portion of the tree which is cut away at its front end and is provided 30 with two recesses 2, 2 into which the lugs 3, 3 of the pivoted toe-piece 4 fits, said toe-piece 4 being shaped to fit the cut-away front end of the foot portion 1, the abutting ends of the toe-piece and foot portion 35 diverge upwardly to permit the outer end of the toe-piece to be raised. A pin 5 passes through the foot portion 1 and through the said lugs 3. The said foot-portion 1 and the toe piece 4 are provided 40 with grooves 6 and 7, extending out to the outer end of the said foot portion and toe piece respectively, in which the adjustable wedge 8 operates to raise and lower the toe piece 4. These grooves 6 and 7 prevent 45 sidewise movement of the said adjustable wedge 8. In the back of the foot-portion 1 is a pivoted screw-threaded bearing 9 adapted to swing on the pin 10 passing through said bearing 9 and said foot-portion 1. 50 This swinging bearing 9 being adapted to assume the proper position relative to the rod 11 when the latter is screwed in or out to raise or lower the toe-piece. The thread-

ed rod 11 passes through said bearing 9 and has on its inner end a pivoted bearing 12 the 55 ends 13 of which fit into the apertures 14 of the wedge 8. The outer end of the rod 11 is provided with a hand-piece 15 by means of which said rod is turned. At the rear of the foot-portion 1 is an adjustable rod 16 having 60 a head 17, said rod 16 being adapted to be screwed in and out to fit the desired size shoe. When the tree is inserted in the shoe, the rod 11 is turned in one direction to force the wedge 8 forward raising the toe-piece 4 65 up tight against the upper and holding the said toe-piece 4 rigid while the operator hammers out any wrinkles or creases in the said upper. When the rod 11 is turned in the opposite direction the wedge 8 will be 70 drawn toward the rear of the tree and allows the toe-piece 4 to drop down and the said tree to be removed from the shoe.

Having thus described my invention, what I claim is:

75 In a shoe-tree the combination of a foot-piece 1 which is cut away at its front end and having a groove 6 in the upper surface of the said cut-away portion extending out to the outer end thereof and a recess 2 in opposite sides of said groove 6, a toe-piece 4 to fit the said cut-away portion of the foot-piece and having a groove 7 in its lower surface coincident with the groove 6 in the foot-piece, lugs 3 projecting downwardly on 80 opposite sides of the groove 7 and adapted to fit into said recesses 2 in close proximity to the abutting edge of the toe-piece and foot-piece, the abutting ends of the toe-piece and foot-piece diverging to permit the toe-piece to be raised at its outer end, a pin 5 85 passing through the said foot-piece and said lugs 3, a threaded bearing 9 pivoted in the rear of said foot-piece, a screw-threaded rod 11 passing through said bearing, and a 90 wedge 8 pivoted to one end of said rod and adapted to be forced back and forth in the grooves 6 and 7 by said rod to raise and lower the toe piece, as and for the purpose set forth.

100 In testimony whereof I affix my signature in presence of two witnesses.

HERMAN G. S. DENKER.
